UNITED STATES PATENT OFFICE.

ALBERT SKOGLUND AND JOHAN BORE, OF GOTTFENBORG, SWEDEN.

BOILER-CLEANER.

1,267,003.

Specification of Letters Patent. Patented May 21, 1918.

Application filed December 11, 1916. Serial No. 136,211.

To all whom it may concern:

Be it known that we, ALBERT SKOGLUND and JOHAN BORE, subjects of the King of Sweden, residing at Gottenborg, in the 5 county of Gottenborg and Bohus and Kingdom of Sweden, have invented new and useful Improvements in Boiler-Cleaners, of which the following is a specification.

This invention relates to such cleaners for 10 the smoke tubes in steam boilers of the usual marine type, which comprise a steam nozzle adapted to be introduced into the combustion chamber behind the smoke tube, ends so that a steam jet can be supplied into the 15 smoke tubes and blow the soot ahead into the uptake or funnel.

The main object of this invention is to provide an adjustable cleaner of the class mentioned adapted to be conveniently used 20 in connection with boilers of different designs and sizes regarding the disposition of the smoke tube ends in the combustion chamber and the width of this chamber, so that the same specimen of cleaner can easily 25 be adjusted to effectively treat all the tubes in a tube bundle. The nozzles for such cleaners, as they are hitherto known, must be properly designed for every special boiler in order that the cleaner may be able 30 to effectively blow out the soot even from the tubes which are most remote from the spot where the cleaner is fitted to the combustion chamber, the distances from this 35 spot to the individual tubes being influenced by the width and by other dimensions of the combustion chamber. Another object of this invention is to make the cleaner adapted to remove the soot or sediment also from the top, bottom, and sides 40 of the combustion chamber laterally to the tube plate. Further objects of the invention are to provide simple and reliable means for shutting off the steam jet, when the cleaner is to be brought out of action, and 45 for securing the cleaner in its non-acting position. Finally one object of the invention is to provide a simple and cheap steam jet cleaner for boiler tubes which can easily be operated by men not specially skilled in 50 handling mechanical tools and to make it durable against the rather severe services in a ship's boiler room.

For the first mentioned object we provide the cleaner with a ball shaped head or nozzle which by the aid of rather simple means 55 can be turned and secured in any arbitrary

angular position relative to the longitudinal axis of the main body of the cleaner, thus dispensing with the necessity to use specially designed heads or nozzles for each 60 individual boiler.

The second object we accomplish by providing the said adjustable head or nozzle with a lateral and secondary aperture for directing the steam jet sidewise on to 65 the top, bottom or side walls of the combustion chamber. Finally we obtain the last mentioned object by means of specially designed steam inlet openings cut offs and locking devices as will be clearly described 70 and ascertained here below.

In the accompanying drawing Figure 1 is a longitudinal section through the improved cleaner in active position, showing portions of the boiler walls between which 75 the cleaner is fitted, Fig. 2 is the same section but in a decreased scale and the apparatus in its non active position. Fig. 3 is a transverse section through the steam nozzle with a portion of the ball shaped nozzle 80 unbroken, Fig. 4 is a longitudinal section through the forward end portion of the apparatus with nozzle, shown in a plane perpendicular to that of Fig. 1. Fig. 5 illustrates the cleaner applied to a marine 85 boiler, of which merely the rear portion with combustion chamber and adjacent portions of furnace and tubes are shown. Fig. 6 illustrates the cleaner from the rear end.

Similar reference figures indicate similar 90 parts throughout the several views.

In a casing 1 with a steam supply pipe 2 is longitudinally movable a tube 3 the outer or rear end of which is closed by means of a screw plug 4 and provided with 95 a handwheel 5. The inner or forward end of the tube 3 carries a screw cap 7 embracing the rotatable, ball shaped steam nozzle 8 which can be secured in any arbitrary angular position by compressing the same between the end 9 of the tube 3 and the screw cap 7. The nozzle 8 is provided with a diametrically throughgoing channel 10 as well as at the surface with an open slot 11 which slot extends throughout nearly a 100 quarter of the circumference of the ball 8. The channel 10 is rather flat in the one direction (Figs. 3 and 4) and in the direction perpendicular thereto spread out from a narrow entrance at the inner end to an 110 extension of approximately a third of the circumference of the ball at the outer end

as clearly shown in Figs. 1 and 2. The screw cap 7 is provided with a narrow slot 12 in the forward end in front of the channel 10 and with a lateral aperture 13 in the 5 boundary of the slot 11 which aperture 13 we prefer to give lengthwise a frusto-conical form with the widest end outwardly. The position of the slot 11 and aperture 13 relative to the steam tube 3 and the center 10 of nozzle 8 is chosen such that the free opening for the steam jet through slot 11 and aperture 13 is not influenced by the angular alteration of the nozzle 8.

In the walls of the tube 3 there are provided 15 a plurality of apertures 14 so positioned that, when the cleaner stands in working position as illustrated in Fig. 1, the apertures 14 open the entrance for the steam from the supply pipe 2 to the interior of the 20 tube 3. When the cleaner, however, is withdrawn to the non-active position as indicated in Fig. 2, the apertures 14 have arrived outside the rear end of the casing 1, thus shutting off the steam supply from pipe 25 2. To avoid steam leakage the tube 3 must be surrounded by a stuffing box 19 with a gland 20, where it leaves the casing 1. Among the apertures 14 two or more are 30 arranged in pairs diametrically opposite one another as may be seen in Fig. 1 in order that in the withdrawn position in Fig. 2 a wedge 15 can be introduced through these two opposite apertures 14 and thus lock the tube 3 in this position against the 35 rear end of the casing 1, by which means the cleaner is prevented from being non-intentionally thrown forward into working position.

To avoid a too far extended withdrawing 40 of the cleaner and to limit this motion the tube 3 adjacent the inner end is provided with a stopping annular surface 16, which in the withdrawn position coöperates with a stopping annular surface 17 at the inner 45 or front end of the spigot 18 of the casing 1, whereby the surface 16 as well as the end surface 17 may be conical, like a valve and its seat, in order to constitute a steamtight joint which can be tightened by pushing in 50 the wedge 15 to any convenient extent. By this means any steam that possibly may pass by from the casing 1 along the outside of the tube 3 will be prevented from escape into the combustion chamber 29 (Fig. 5).

55 The stuffing box 19 is provided with a prong 21 and a locking device 23 which is pivotable about a fulcrum 22 and provided with two hook shaped prongs 24, which co-operate with an annular slot 25 in wheel 60 hub 26, when the cleaner is in working position (Fig. 1). The last mentioned device prevents the tube 3 from being thrown rearward by reaction from the steam pressure, without interfering with the free revolving 65 of the tube 3 by means of the handwheel 5.

The application of the cleaner to a boiler is carried out in the usual way, so that the casing 1 is attached to the rear wall 27 of the boiler with the spigot 18 introduced into a tube 28 going between the wall 27 and 70 the opposite wall 30 of the combustion chamber 29.

The cleaner works as follows: In the withdrawn position shown in Fig. 2 the steam supply to the tube 3 from pipe 2—to which 75 the steam is supplied from the steam space in boiler by means of a pipe 6 (Fig. 5)—is shut off and the tube 3 locked in said position by means of the wedge 15, so that the nozzle 8 is kept in the tube 28 well protected 80 from the hot gases in the combustion chamber 29. Having removed the wedge 15 the tube 3 can be pushed ahead so far, that the nozzle 8 enters the combustion chamber 29, and that the apertures 14 establish communication 85 between the pipe 2 and the interior of tube 3, whereby the steam can find its way into the combustion chamber through the channel 10. The steam jet attains a spread somewhat as indicated by the full lines in 90 Fig. 5 and acts upon the lower portion of the tube bundle 31. By turning the tube 3 around its longitudinal axis by means of the handwheel 5 the steam jet, which is laterally somewhat flattened on account of 95 the narrow shape of channel 10 (see Figs. 3 and 4), will be caused to act successively on all the tubes in the tube bundle 31 as indicated by the dot and dash lines in Fig. 5. The slot 11 and aperture 13 (Fig. 4) serve 100 to supply a steam jet also on to the top, bottom, and side walls in the combustion chamber as the apparatus is made to revolve by means of the handwheel thus cleaning even those parts from soot. In Fig. 5 this 105 lateral steam jet is not illustrated.

The ball shape of the nozzle 8 and the manner in which the nozzle is secured to the tube 3 by the screw cap 7 allows the nozzle to be adjusted so as to get the channel 110 10 positioned in the most favorable angular direction relatively the middle line of the tube 3, when fitted to the boiler, by which means it will be possible to cause the steam jet to effectively reach all the smoke tubes 115 31, independent of in what direction to, or at what distance from the spot in the wall 30 where the cleaner is fitted. The same specimen of nozzle 8 thus can be used for boilers of any sizes and no need for a special 120 designed nozzle for each specimen of boiler will occur.

Having thus described our said invention and how it is to be performed, what we claim as new and want to protect by Letters Patent is:

1. A boiler cleaner comprising a steam supply pipe, a steam tube communicating with the supply pipe and mounted for rotation, means for positively rotating the 130

said tube, a steam nozzle carried by the steam tube for rotation therewith and mounted for angular adjustment with relation to the axis of the latter, and means for 5 securing the nozzle in adjusted position.

2. A boiler cleaner comprising a steam supply pipe, a steam tube communicating with the supply pipe and mounted for rotation, means for rotating the said tube, a 10 steam nozzle carried by the steam tube for rotation therewith and mounted for angular adjustment with relation to the axis of the latter, the said nozzle having a main delivery channel adapted to be adjusted angularly by turning the nozzle, means for 15 securing the nozzle in adjusted position, and means operable by said nozzle for delivering a jet laterally from the nozzle in fixed angular relation to the axis of the steam 20 tube irrespective of adjustment of the nozzle.

3. A boiler cleaner comprising a steam supply pipe, a steam tube communicating with the supply pipe and mounted for rotation, means for rotating the said tube, the 25 said tube having a spheroidal socket at its outlet end and a lateral secondary delivery opening adjacent thereto, a spheroidal steam nozzle fitting adjustably in the said socket and having a diametrical delivery channel 30 which is flaring outwardly in one direction and narrow in a direction at right angles thereto so as to produce a fan-like jet and the outlet end of which is contracted medially and wider at the sides, the nozzle being provided further with a secondary delivery slot which is disposed so as to be in 35 communication with the interior of the steam tube and the said secondary delivery opening at all times irrespective of angular adjustment of the nozzle, and means for securing the nozzle in adjusted position.

4. A boiler cleaner comprising a steam supply pipe, a casing communicating with 45 the supply pipe and having alining stuffing boxes, a steam tube extending through the casing and fitting the stuffing boxes for rotation and reciprocation therein, the said tube being closed at one end and having 50 lateral apertures intermediate of its ends adapted to establish communication between the steam supply pipe and the interior of the said tube when the latter is in its operative position, the steam tube being adapted 55 to be withdrawn into inoperative position

with the said apertures disposed outside the casing, a delivery nozzle provided at the open end of the steam tube, and means for operating the said tube.

5. A boiler cleaner comprising a steam 60 supply pipe, a casing communicating with the supply pipe and having alining stuffing boxes, a steam tube extending through the casing and fitting the stuffing boxes for rotation and reciprocation therein, the said tube being closed at one end and having lateral apertures intermediate of its ends adapted to establish communication between the steam supply pipe and the interior of the said tube when the latter is in 70 its operative position, the steam tube being adapted to be withdrawn into inoperative position with the said apertures disposed outside the casing, a delivery nozzle provided at the open end of the steam tube, and 75 means for operating the said tube, at least two of the apertures in the tube being arranged in transverse alinement, so that a wedge can be introduced through the two diametrically arranged apertures for the 80 purpose of locking the cleaner in the withdrawn position.

6. In a boiler cleaner the combination of a steam supply pipe, a steam tube communicating therewith, a steam nozzle, a delivery channel penetrating said nozzle in the longitudinal direction of the steam tube, and means for changing the angular position of said nozzle in relation to the longitudinal axis of said tube, a casing embracing the rear portion of said steam tube, said casing being secured to the boiler which is to be cleaned, and a hand wheel fixed on the rear end of the steam tube adapted to make the tube revolve inside the casing, the wheel hub being provided with an annular groove, a pivotable locking device on the casing, provided with prongs, which coöperate with the annular groove in the wheel hub, for the purpose of preventing the non intentional withdrawing of the cleaner caused by the reaction of the steam, when the apparatus is in working position.
